Primary Examiner—Jennifer Rivard

(**) Term: **14 Years**

(74) Attorney, Agent, or Firm—Stetina Brunda Garred & Brucker

(21) Appl. No.: **29/166,257**

(57) **CLAIM**

(22) Filed: **Aug. 23, 2002**

The ornamental design for a light emitting diode headlight ring, as shown and described.

(51) LOC (7) Cl. **26-99**

DESCRIPTION

(52) U.S. Cl. **D26/139**

FIG. 1 is a top plan view of the light emitting diode headlight ring of the presenting invention showing my new design; FIG. 2 is a front elevation view thereof; FIG. 3 is a side elevation view thereof; FIG. 4 is a rear elevation view thereof; and, FIG. 5 is a bottom plan view thereof.

**EX PARTE
REEXAMINATION CERTIFICATE
ISSUED UNDER 35 U.S.C. 307**

AS A RESULT OF REEXAMINATION, IT HAS BEEN
DETERMINED THAT:

Claim 1 is cancelled.

The ornamental design for a light emitting diode headlight
ring, as shown and described.
